UNITED STATES PATENT OFFICE.

JOSEPH KOZIOL, OF MILWAUKEE, WISCONSIN, ASSIGNOR OF ONE-FOURTH TO BOLESŁAW GRABOWSKI, OF MILWAUKEE, WISCONSIN.

SHADE AND CURTAIN HOLDER.

Application filed September 21, 1922. Serial No. 589,623.

To all whom it may concern:

Be it known that I, JOSEPH KOZIOL, a citizen of Poland, residing at Milwaukee, in the county of Milwaukee and State of Wisconsin, have invented certain new and useful Improvements in Shade and Curtain Holders, of which the following is a specification.

This invention relates to new and useful improvements in combination shade and curtain holders, and has for its primary object thereof the provision of such an article of manufacture that may be easily and expeditiously applied to window frames of varying diameters, and when once installed will remain in an operative position until removal of the same is desired.

A further object of this invention is to devise such a shade and curtain holder having means associated therewith for rigidly engaging the same to the window frame and one wherein no such fastening means such as nails or the like need be employed.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a top plan view partly in longitudinal section of my device showing the same in applied position upon the window frame, the said window frame being disclosed in dotted lines and also disclosing the curtain pole associated therewith,

Figure 2 is a front plan view of the device shown in Fig. 1 also setting forth in dotted lines the window shade supported thereby,

Figure 3 is a fragmentary transverse longitudinal sectional view of a portion of one of the window frame engaging members,

Figure 4 is a transverse sectional view upon the line IV—IV of Fig. 3 and looking in the direction of the arrows,

Figure 5 is a plan view of the blank from which portions of my device are formed,

Figure 6 is a fragmentary elevational view of one end of a modified form of my invention,

Figure 7 is a vertical sectional view upon

the line VII—VII of Fig. 6 looking in the direction of the arrows, and

Figure 8 is a fragmentary top plan view of a still further modified form of the present invention.

Referring more in particular to the several views, there is disclosed in outline in Fig. 1 a window frame comprising the usual wooden side frame elements 1 and 2 to which is adapted to be detachably secured at any convenient point thereon my improved device. The invention comprises inter-connected bracket elements 3 positioned for flat engagement with the outer faces of the side frame members 1 and 2 and having right-angularly bent end portions 4 with inwardly bent projecting prongs 5 formed thereon for biting into the walls of the side frame in a manner hereinafter more fully described. Upon the opposite ends of each of the brackets 3 there is formed a sleeve portion 6 adapted for tightly receiving the opposite ends of a telescopic rod 7. Upon the hooked ends of the brackets 3 there is also formed tubular members 7' flared at their outer ends as at 8 and being so bent as to have these flared outer ends substantially parallel to the longitudinal axis of each of the brackets 3. Positioned for detachable engagement with the flared ends of these tubular portions 7 are the opposite end portions of a telescopic curtain supporting rod 9. The brackets 3 have further formed thereon a depending leg portion 10 having forwardly projecting shade roller bracket members 11, each of the same being suitably slotted or perforated as at 12 for receiving the flat or round end of the shade roller shaft.

As before stated, a telescopic rod 7 is adapted to be tightly received at its opposite ends within sleeve portions 6 formed upon the brackets 3, and it is to be herein noted that this telescopic rod functions as an adjustable interconnecting means between the opposite brackets 3 upon the side frames 1 and 2 of the main window frame. This telescopic rod 7 is formed of two hollow tubular rod members 13 and 14, the said rod 14 being of a slightly lesser diameter than the rod 13 whereby the same may be slidably positioned therein. Extending through each of the rod members and rigidly secured at its opposite ends, as at 15, to the inner end portions of the bent tubes 7', formed

upon each of the brackets 3, is a relatively strong coil spring 16. This coil spring 16 functions as a tensioning means between the opposite bracket members 3, and in view of this spring member and the telescopic rod 7, rigidly carried by the opposed brackets, the device may be readily extended so as to fit upon window frames of varying diameters, and it will be further noted that when the device is so extended as to engage over the side members of a main window frame the teeth or prongs 5 of each of the brackets will be caused to bite into the side walls of the window frame to be there retained in a permanent position.

In Fig. 5 of the drawing, I have disclosed a sheet metal blank so cut as to form the bracket members 3 and its closely associated parts. This blank comprises a main section 3' of substantially rectangular formation and of any preferred design. Formed upon one of the side edges of this main section are V-shaped projecting legs 4' adapted to be bent inwardly at right angles upon the main section 3' for forming the side flanges 4 as previously described. The extreme outer edges of these projecting V-shaped legs may be also inwardly bent for forming the teeth or prongs 5 for biting into the side edges of the window frame. Between the V-shaped legs 4' of the main section 3' the same has formed thereon a strip of material 7" which strip of material is adapted to be so bent as to form the tubular curtain rod receiving portion of the main bracket 3. The opposite side of the main section 3' of the blank is provided with upper and lower ear sections 6' whereby the same are to be so bent as to function as the sleeve portions 6 of each of the brackets. Further, the main section of the blank has a depending leg portion 10 adjacent the sleeve end thereof which depending leg has a bracket member 11, formed thereon which bracket member is adapted to be bent at right angles to the leg portion 10 for receiving the ends of the shade roller.

In Figs. 6 and 7 I have shown a modified form of window frame engaging bracket having means incorporated directly therein for rigidly securing the said bracket to the upper and lower edges of the upper longitudinal cross member of the window frame.

In this form of the invention, the device is only adaptable for supporting a curtain pole of a particular design. As shown the device comprises a relatively short hollow tube 17 having formed upon its upper edge portion downwardly projection prongs 18. This tube 17 is of the open end type and has at its upper open end a solid head member 19 carrying a depending skirt portion 20 for positioning within the said tube. At the lower end of the said tube there is provided a flat plate member 21 having a leg portion

22 formed thereon for positioning within this end of the said tube; and it is to be noticed that this leg portion 22 is resiliently held within the tube by a coil spring 23, the opposite ends of which are secured within 70 perforations of the portion 20 of the head 19 and the said leg of the plate member 21. This plate member 21 is provided with a finger engaging piece 24 and it will be readily noted that these bracket members may be 75 secured upon the window frame by engaging the prongs 18 and the outer end of the plate member 21 upon the opposite edges of the said frame.

It will be further understood that two of 80 these brackets are to be employed by me and are to be positioned at a distance from each other according to the length of the curtain pole to be used. The tubular portion 17 of each of these bracket members have formed 85 thereon a pole retaining means comprising a strip of sheet material overturned at its upper and lower edges defining a guideway 25 therein for the reception of the opposite end portions of a flat like curtain pole 26, 90 the said pole retaining member formed on the tube 17 being designated by the numeral 24'.

In Fig. 8 there is shown a slightly modified form of the invention as disclosed in 95 Figs. 1 to 4 inclusive and in this modification the device merely comprises means for supporting a plurality of curtain poles 9, and in this instance the bracket 3 in addition to having the curtain pole supporting 100 element 7' as hereinbefore described is also provided with an additional supporting means 9' of a construction substantially similar to the support 7'.

It is believed that the advantages and the 105 operation of my invention will be readily understood, and it is to be herein noted that minor changes may be made in the invention without departing from the spirit and scope thereof as claimed.

What I claim is:—

1. In a window shade and curtain pole supporting bracket formed from a single sheet metal blank cut and bent to form a bracket section, anchoring prongs, a curtain pole supporting means, a shade roller supporting member, and a resilient clamping rod supporting means; the said sheet metal blank comprising a main bracket section, a longitudinally extending strip carried by one end thereof, a pair of V-shaped legs carried by said bracket section end and positioned on either side of said strip, a leg extending laterally from said bracket section, a bracket member carried by said leg, and a pair of opposed ears carried by the remaining end of said bracket section.

2. In a device of the class described, a pair of oppositely disposed bracket members adapted for engagement upon the vertical 130

side members of a window frame, each of said brackets being formed from a single sheet metal blank cut and bent to comprise a main body section, a longitudinally extending strip carried by one end of said body section and adapted to be formed into a tubular member having a flared outer end for receiving one end of a telescopic curtain pole, a pair of V-shaped legs positioned on opposite sides of said strip having their ends bent to form prongs for biting into a vertical side of the window frame, a depending leg portion carried by the opposite end of

said body section, a shade roller supporting bracket carried by said depending leg and bent at right angles thereto, and a pair of opposed ear sections carried by the last mentioned end of said body section and adapted to be bent to form a sleeve for rigidly receiving one end of a resiliently connected telescopic rod adapted for drawing the said pair of window frame engaging bracket members toward each other for removably securing the entire device to said frame.

In testimony whereof I affix my signature.
JOSEPH KOZIOL.
